UNITED STATES PATENT OFFICE.

ROY EVERHART, OF MARSHALL, TEXAS, ASSIGNOR TO HIGHWAY ADVERTISING CO.,
OF MARSHALL, TEXAS.

DESIGN FOR AN ADVERTISING SIGN.

Application filed July 14, 1926. Serial No. 18,362. Term of patent 14 years.

To all whom it may concern:

Be it known that I, ROY EVERHART, a citizen of the United States, residing at Marshall, in the county of Harrison and State of Texas, have invented a new, original, and ornamental Design for an Advertising Sign, of which the following is a specification, reference being had to the accompanying drawing, forming part thereof.

Figure 1 is a front elevation of an advertising sign showing my new design.

Figure 2 is an edge elevation thereof. The central plain field shown in Figure 1 of the drawing is intended as an outline map of a geographical subdivision.

I claim:—

The ornamental design for an advertising sign, as shown and described.

ROY EVERHART.
